[57] CLAIM

The ornamental design of an apex member for use in a pyramid structure, as shown and described.

DESCRIPTION

FIG. 1 is a side elevational view of an apex member for use in a pyramid structure and embodying my design, the other three sides being identical.

FIG. 2 is a top plan view thereof.

FIG. 3 is a bottom plan view thereof.

FIG. 4 is a fragmentary corner elevational view thereof taken on line 4—4 of FIG. 1.

FIG. 5 is a fragmentary transverse sectional view taken on line 5—5 of FIG. 4.
